ABRASIVE STONE HOLDER

Maurice N. Prange, Detroit, Mich.

Application March 12, 1934, Serial No. 715,238

7 Claims. (Cl. 51—184.1)

This invention relates to an abrasive stone holder or abrasive element for grinding tools, and has as its objects to simplify, render more efficient, and improve generally devices of this character.

One of the important objects of the invention is to provide a backing member for abrasive stones having novel and improved means for anchoring the abrasive element therein together with simple but effective means for positioning the backing member relative to the abrading element receiving member of the hone or grinding tool.

The above, as well as other objects of the invention, together with the novel details of construction, will be made more apparent as this description proceeds, especially when considered in connection with the accompanying drawing, wherein.

20 Figure 1 is an end elevation of a honing tool provided with my improved abrasive stone holder;

Figure 2 is a perspective view of the backing or channel member;

25 Figure 3 is a side elevation thereof with the abrasive element secured therein;

Figure 4 is an enlarged transverse sectional view taken substantially on the plane indicated by line 4—4 in Figure 3;

30 Figure 5 is a similar view taken substantially on the plane indicated by line 5—5 in Figure 3;

Figure 6 is a top plan view showing my improved abrasive element including the backing member associated with the abrasive element receiving member, and

35 Figure 7 is a view similar to Figure 6 with the positioning means carried by the backing member engaging the end faces of the receiving member.

40 Referring now more particularly to the drawing wherein like reference characters indicate like parts, it will be noted that there is illustrated in Figure 1 a rather conventional form of honing tool 10 provided with a plurality of radially extending outwardly opening recesses 11 in which a corresponding number of abrading element receiving members 12 are mounted for radial adjustment in any preferred or desired manner by means not shown herein as it forms no important part of this invention.

45 My improved abrasive element comprises a relatively shallow channel or backing member 13 in which the abrasive element or stone 14 is adapted to be secured. The channel back-

ing member may be provided with one or more apertures 15 in the base thereof and with one or more apertures 16 in either or both of the side flanges thereof. In practice, I may employ only the apertures 15 or only the apertures 16, 5 or I may provide both the apertures 15 and 16, as illustrated.

The abrasive stone is formed in the channel by means of a mold or the like and when molding the stone in the channel the material from 10 which the abrasive element is formed extends into and fills the apertures 15 and 16 and produces projections or dowels 17 and 18 engageable in these apertures to anchor the abrasive element in the backing member. This is most 15 clearly illustrated in Figures 4 and 5.

Either one or both ends of the flanges of the channel shaped backing members are provided with extensions 19 adapted to be bent laterally, as shown at 19' in Figure 7, to engage the end 20 faces of the receiving members 12 to thus position the backing member and abrasive stone in the receiving member. These extensions 19 are preferably bent laterally into engagement with the end faces of the receiving member 12 25 after the backing member with the abrasive stone seated therein has been positioned in the receiving channel of the receiving member. This obviously provides an efficient but simple means for preventing relative longitudinal movement between the receiving member and the abrasive element. 30

For holding the abrasive elements and receiving members in assembled relation on the honing member 10, extensions 21 are provided 35 on the backing member or channel, which extensions are provided with apertures 22 to receive the ends of springs 23 which, as will be obvious, hold the abrasive elements in assembled relation but permit radial adjustment 40 thereof.

The dowel pin-like projections 17 assist in anchoring the abrasive element against longitudinal movement relative to the backing member, whereas the dowel pin-like projections 18 45 effectively anchor the abrasive element against longitudinal and perpendicular movement with respect to the channel backing member. Moreover, by molding the stone in the backing member an integral unitary structure is produced. 50

While the embodiment of the invention herein illustrated has been found in practice to produce satisfactory results, nevertheless reservation is made to make such changes in the 55

details of construction as may come within the purview of the accompanying claims.

What I claim as my invention is:

- 5 1. An abrasive element for a grinding tool comprising a channel member provided with apertures in the side flanges thereof, and an abrasive stone secured in said channel and having portions thereof projecting into said apertures.
- 10 2. An abrasive element for a grinding tool comprising a channel member having apertures in the base thereof and an abrasive stone secured in said channel and having portions thereof projecting into said apertures.
- 15 3. An abrasive element for a grinding tool comprising a channel member having apertures in the base and side flanges thereof and an abrasive stone secured in said channel and having portions thereof projecting into said apertures.
- 20 4. An abrasive element for a grinding tool comprising a channel member having an aperture extending through one wall of the channel, and an abrasive stone within the channel provided with an integral dowel extending into the aperture for securing the stone within said channel member.
- 25 5. In an abrasive unit for a honing tool, a channel member, an abrasive stone having integral projections extending laterally therefrom, a retainer for the stone engageable in the first channel and comprising a second channel
- 30

member having openings therethrough for receiving the projections on the stone to secure the latter thereto and having projections extending laterally from opposite ends thereof engageable with the extremities of the first channel to prevent relative longitudinal movement between the channel members.

5 6. In an abrasive unit for a honing tool, a channel member, an abrasive stone having laterally extending integral projections thereon, a 10 retainer for the stone engageable in the channel member and comprising a second channel member having apertures therethrough for receiving the projections on the stone to secure the latter thereto, and lugs projecting laterally 15 from the extremities of one of the channel members for engaging the ends of the other channel member to prevent relative longitudinal movement of said members.

7. In an abrasive unit for a honing tool, a 20 channel member, an abrasive stone having integral laterally extending projections, a retainer for the stone engageable within the channel of said member and comprising a second channel member having openings therethrough for 25 receiving the integral projections to secure the stone thereto and having lugs projecting laterally outwardly from the extremities of the side flanges of the channel for engaging the opposite ends of the side flanges of the first 30 named channel.

MAURICE N. PRANGE.
